United States Patent Office.

WILLIAM HAILES, OF ALBANY, NEW YORK, ASSIGNOR TO JOHN F. RATHBONE AND COMPANY, OF SAME PLACE.

Design No. 3,205, dated September 22, 1868.

DESIGN FOR A STOVE.

The Schedule referred to in these Letters Patent and making part of the same.

TO ALL WHOM IT MAY CONCERN:

Be it known that I, WILLIAM HAILES, of the city of Albany, State of New York, have invented or produced a new, useful, ornamental, and original Design for Parlor-Stoves, (stove being named "The Extension-Top Brilliant Heater;") and I declare the annexed drawing, exhibiting in perspective the stove, to be a full and accurate delineation of its plates, with their ornaments, parts of the stove not shown being symmetrically similar to the parts shown.

What I claim, and desire to secure by Letters Patent, is—
The design for the parlor-stove, as herein shown and described.
